UNITED STATES PATENT OFFICE.

WILL ESPY CURTIS, OF EVANSTON, ILLINOIS.

TRACTION APPARATUS.

Application filed June 19, 1922. Serial No. 569,479.

This invention relates broadly to traction devices, and more particularly pertains to an improved portable traction operated hoisting device, especially adapted for employment in extracting tree stumps, posts, and for other similar purposes.

While this invention is illustrated and described as a stump extractor, it will be understood that I do not limit the invention to this 10 adaptation, but that the device finds a large field of utility for other purposes.

This invention is designed, among other things to appear later, as another development of the invention illustrated, described 15 and claimed in my co-pending application, Serial Number 557,531, and therefore this device has some features, and advantages, in common with the device of the application mentioned.

20 The principal objects and advantages which characterize this invention are expressed in the provision of improved means for imparting motion; the provision of improved portable means for imparting motion; 25 the provision of improved means for hoisting and similar purposes; the provision of improved means for extracting various objects imbedded in the ground, such as tree stumps and the like; the provision of improved portable hoisting apparatus characterized by the presence of an improved means 30 for anchoring same; the provision of improved means for hoisting characterized by the provision of a portable source of power 35 and associated hoisting mechanism; the provision of an improved arrangement of portable source of power, propelling and hoisting means, and means for anchoring the source of power; and the provision of a traction operated portable hoisting device embodying 40 the foregoing advantages and features and such other advantages and features as may hereinafter appear which is simple in construction and efficient in operation.

45 The foregoing and such other objects and advantages as may appear or be pointed out as this description proceeds are attained in the structural embodiment illustrated in the accompanying drawings, in which:

50 Figure 1 is a side elevational view of a device involving the improvements of this invention;

Figure 2 is a top plan view of the same;

55 Figures 3 and 4 are enlarged longitudinal vertical sectional views taken on the lines 3—3 and 4—4 respectively of Figure 2, look-

ing in the direction indicated by the arrows.

Referring now more particularly to the drawings, and first more especially to Figures 1 and 2, there is provided a frame or chassis A composed of the spaced side I-beams 5 and 6, fixedly connected near one end by a platform plate 7, the latter being strengthened by an angle-bar 8. The I-beams 5 and 6 are secured to the plate 7 and angle-bar 8 by a series of rivets 9—9 or the like. The plate 7 terminates at approximately the medial portion of the chassis and thereby leaves a space 10 toward one end for accommodation of certain parts to be later 70 described.

One end of the chassis, which may be termed the rear end for convenience, is provided with an axle 11, said axle having reduced end portions 12 and 13 projecting 75 transversely beyond the side I-beams and rotatably supporting the hubs 14 and 15 of traction wheels 16 and 17, respectively. The axle 11 is fixedly mounted in bearing brackets 18—18 secured, by rivets 19 or the like, to 80 the top surfaces of the I-beams 5 and 6. The traction wheels 16 and 17 are here shown as of the disk type, and are provided with peripheral projections 20—20 for impinging engagement with the earth in the well-known manner. Each wheel is provided, on its internal face, with a gear, said gears being designated 21 and 22, respectively.

85 The forward end of the chassis, that is, the portion carrying the platform 7, is supported on a steering element, such as a wheel 23, revolvably mounted in a fork member 24, the latter having a trunnion 25 extending through a suitable bearing 26, carried by the platform 7. A bevel pinion 27 is fixedly mounted upon the upper end of the trunnion 25, and a second bevel pinion 28 meshes with said pinion 27, the pinion 28 being fixedly mounted on the lower end of an inclined steering post 29, mounted in a bearing 30 mounted upon the 90 platform 7. A steering wheel 31 is secured to the upper end of the shaft or post 29.

95 This invention includes the propelling and hoisting mechanisms, together with means for anchoring the chassis against movement, this 100 means embodying a ground engaging element, such as the angularly adjustable frame B, and means for manipulating such anchoring device. The frame or anchor B comprises spaced bars 32 and 33, arranged each on the outside of the chassis, between the planes of the traction wheels 16 and 17 and side I-

110

beams 5 and 6. The frame B is angularly adjustable about the axle 11 as a center, and to this end the rear ends of the bars 32 and 33 are provided with bearing brackets 34 and 35 respectively, said bearing brackets being receivable upon the reduced ends 12 and 13 of the axle, between the wheel hubs and the bearings or axle supports 18—18. Thus the bearings 34 and 35 serve to space the wheels from the chassis by abutment with the wheel hubs and the bearings 18. The forward ends of the bars 32 and 33 terminate beyond that end of the chassis, and are connected by a transverse spade or shoe 36, fastening brackets 37—37 serving to secure the shoe to the bars. The shoe is provided with a toothed lower edge 38 to facilitate engagement with the earth. The anchoring device is angularly manipulated by imparting rotation to a transverse shaft 39 mounted in bearings 40 on the platform 7, the ends of said shaft having sheaves 41—41 secured thereto, to which sheaves are secured cables 42—42, which latter are also fixedly secured to one each of the side bars 32 and 33. A lever 43 is freely oscillatably mounted on the shaft 39, and a pawl 44, carried by the said lever, serves to engage a ratchet wheel 45 fixed on the shaft 39. The lever is, of course, limited against movement in one direction beyond a predetermined point, such as the vertical location of the lever as shown in Figure 1. An abutment 46 on one of the bearings 40 serves this purpose. A second pawl 44^a engages the ratchet wheel 45 for latching same.

Referring now to the propelling and hoisting mechanisms, I provide a prime mover, such as an internal combustion engine 48, mounted upon the platform 7, the crank shaft 49 of said engine being disposed transversely to the longitudinal axis of the device. A pinion 50 is fixedly carried on one end of the crank shaft 49 and meshes directly with a reduction gear 51, which latter is fixedly mounted on the inner end of a stub shaft 52, mounted in a bearing 53 on said platform. Of course, it will be readily understood that the direct connection of the pinion 50 and gear 51 may be substituted for or supplemented by a conventional speed change gearing, such speed change gearing forming in detail no part of this invention, and therefore being omitted from the drawing.

On the shaft 52 there is also fixedly mounted a sprocket wheel 54, about which a power transmission chain 55 is trained, said chain being furthermore trained over a sprocket wheel 56, which latter is fixedly mounted on a clutch shaft 57, said clutch shaft having various clutch elements thereon, and being revolvably mounted in suitable bearing elements 58 and 59 supported by the I-beams 5 and 6. Reference may be now further had to Figures 3 and 4.

65 Power is transmitted from the clutch shaft to the traction elements at different rates of speed in desired directions by the provision of a propelling shaft 60, revolvably mounted in bearings 61 and 62 in the brackets 63 and 64, secured to the I-beams 5 and 6, said shaft 60 extending between the traction wheels and having pinions 65—65 on the ends, which pinions mesh with the drive gears 21 and 22. Sleeves 66—66 on said shaft 60 prevent longitudinal displacement of said shaft by abutment with the bearings 61 and 62. A sprocket wheel 67 is fixedly mounted upon the shaft 60 and a sprocket chain 68 is trained over said sprocket wheel, and over a complementary, but smaller sprocket wheel 69, fixedly carried by the speed change gear shaft 70, which latter receives its motion from the clutch shaft 57, through speed change gears 71—72 and a speed change gear 73 and pinion 74, respectively. The gears 71 and 73 are fixedly secured to shaft 70, and the pinion 74 is loosely mounted on clutch shaft 57. The gear 72 is rotatably mounted on a stub shaft 75, carried by the bracket 58, and said gear is operatively connected with the clutch shaft through meshing engagement with a pinion 76 loosely mounted on said clutch shaft near the sprocket wheel 67. The pinions 74 and 76 are each provided with clutch faces 77 and 78, respectively, and a clutch block 79 is disposed between said pinions and slidably keyed for rotation with said shaft 57. A lever 80 is manipulated to engage the clutch with one or the other of said pinions for imparting rotation thereto, so that, upon which pinion is engaged, depends the speed and direction of propulsion of the vehicle.

The hoisting mechanism which I provide comprises the winding drums 81 and 82 freely rotatably mounted coaxially upon the axle 11, between the side frame members 5 and 6, said drums being each provided with spiral grooves 83 and 84. Between the drums 81 and 82, and fixedly secured to each, there is provided a relatively large gear 85, said gear being in meshing engagement with a pinion 86, fixedly secured to the transverse hoisting drum drive shaft 87, the latter being revolvably mounted in bearing members 88—88 secured to the under surfaces of the I-beams 5 and 6. Near one end of the shaft 87 there is fixedly secured a sprocket wheel 89, over which is trained a sprocket chain 90, said chain in turn being trained over a relatively smaller sprocket wheel 91 fixedly secured to the shaft 92, said shaft 92 being termed the winding drum reduction gear shaft. The shaft 92 is mounted in bearings 93—93 formed in the bearing brackets 63 and 64, and as shown in the Figure 1, this shaft 92 is disposed in a plane slightly above the clutch shaft 57, but below the plane of the shaft 70.

65 The shaft 92 receives motion in one direction and at a given speed from the clutch

130

shaft, by the provision of a sprocket wheel 95 on said shaft 92, sprocket chain 96, and sprocket wheel 97 freely rotatable on the shaft 57, the sprocket chain being trained over said sprocket wheel. Motion is imparted to the shaft 92 in another direction, and at the same speed as that of the clutch shaft 57, by the provision of intermeshing gears 98 and 99, the gear 98 being fixedly secured to the shaft 92, and the gear 99 being freely rotatable on the clutch shaft. The sprocket wheel 97 is provided with a clutch face 100, and the gear 99 is provided with a similar clutch face 101, and between, and adapted for engagement with either of said clutch faces, there is provided a slideable clutch block 102 operable by a lever 103 and slideable on said shaft 57.

A flexible motion transmitting element is provided, such as flexible cable 104, said cable having its ends secured to one each of the drums 83 and 84, respectively, as best observed in Figure 2, in order to form a loop 105. The two parallel, or substantially parallel, portions of the cable extend on either side of the steering wheel fork 24, and the loop 105 receives a sheave 106 mounted in a bracket element 107, the latter being provided with an object engaging hook 108.

In operation, the machine described is propelled to a suitable point of vantage by starting the engine 48 and moving the clutch block 79 into engagement with the clutch face 78, the clutch shaft 57 rotating in the direction of the arrow R in Figure 4. Engagement of the clutch 79 as explained propels the device in the forward direction, or toward the right hand end as viewed in Figure 1. The device is steered to a desired position by manipulation of the steering wheel 31. By moving the clutch 79 into either of its engaging or driving positions, the operator is enabled to maneuver the apparatus until the desired relationship thereof to the object to be hoisted is attained. The anchoring device is now dropped by releasing the pawl 44^a and the spade 36 engages and is forced into the earth by the movement of the machine. Thereupon the clutch 79 is left in neutral position.

The machine now being in the desired position, the cable 104 is "paid out" by engaging the clutch 102 with the clutch face 101, on the gear 99, which causes the drums 83 and 84 to rotate counter-clockwise as viewed in Figures 3 and 4. The hook 108 is now lashed or otherwise properly attached to the object to be moved, or is attached to such object through a purchase-increasing element, such as a conventional block and tackle arrangement. The anchoring device being lowered and the blade 36 engaging the earth, the clutch element 102 is now moved to engage the sprocket clutch face 100. This imparts rotative motion to the drums 83 and 84

in a clockwise direction as viewed in Figures 3 and 4, this causing the cable 104 to be wound upon both drums. The tension thus set up causes the anchor to become embedded, thus preventing movement of the machine toward the object. As practically all the weight is on the traction wheels, and as the plane of pull or tension is directed below the axle 11, tilting or upsetting of the apparatus is rendered impossible. Furthermore, the wide spade employed in the anchor, and the fact that the direction of movement is in a plane substantially coincidental with that of the longitudinal axis of the machine, prevents sidewise displacement of the apparatus in hoisting.

When the work to be accomplished is completed, the cable is disconnected from the object moved, and the machine is backed away, which, together with manipulation of the anchor hoisting lever 43, raises the anchor to inoperative position. Backing of the machine is accomplished by moving the clutch 79 into engagement with the pinion clutch face 77.

It will be seen that when "paying out" the cable, the rate of speed of the drums relative to the clutch shaft 57 is higher than when hoisting, because when hoisting, speed must be secondary to power. This relationship is attained by the provision of the sprocket wheels 95 and 97 of different diameters, and the gears 98 and 99 of the same diameters. The same ratio, in effect, is true of the propelling arrangement afforded by the provision of the gears 71, 72, 76, 74 and 77, so that in the forward motion the vehicle is propelled faster than when in the reversed motion, for a given speed of the clutch shaft 57. Thus, where it is desired to employ both the traction wheels and the drums in moving an object, the utmost power is obtainable. By extending the cable from the other end of the machine than that shown, the device may be employed for towing, and for other similar purposes.

Having thus described my invention and illustrated its use, what I claim as new and desire to secure by Letters Patent is:

1. In a device of the character described, in combination, a chassis, supporting traction wheels for said chassis, a source of power on said chassis, an axle for said wheels, a revoluble shaft for driving said wheels, a hoisting drum concentric with said axle, a revoluble shaft for driving said drum, a gear train for driving said first mentioned revoluble shaft, a companion gear train for driving the other of said revoluble shafts, a counter-shaft, driven by the source of power and common to said other shafts, and clutch members mounted upon said counter-shaft for alternately or simultaneously engaging said gear trains for driving said shafts.

2. In a device of the character described,

in combination, a chassis, supporting traction wheels for said chassis, a source of power on said chassis, an axle for said wheels, a revoluble shaft for driving said wheels, a 5 hoisting drum concentric with said axle, a revoluble shaft for driving said drum, a gear train for driving said first mentioned revoluble shaft, a companion gear train for driving the other of said revoluble shafts, a counter- 10 shaft, driven by the source of power, each of said gear trains having forward and reverse driving gears loosely mounted upon said counter-shaft, and two clutch elements splined upon said counter-shaft and adapted 15 to engage either the forward or the reverse gear of the two gear trains respectively.

3. In a device of the character described, in combination, a chassis, supporting traction wheels for said chassis, a source of power on 20 said chassis, an axle for said wheels, a revolu-

ble shaft for driving said wheels, a hoisting drum concentric with said axle, a revoluble shaft for driving said drum, a gear train for driving said first mentioned revoluble shaft, a companion gear train for driving the other 25 of said revoluble shafts, a counter-shaft driven by the source of power, each of said gear trains having forward and reverse driving gears loosely mounted upon said counter-shaft, and two clutch elements splined upon 30 said counter-shaft and adapted to engage either the forward or the reverse gear of the two gear trains respectively, and separate operating elements for said clutch members, whereby said traction wheels and hoisting drum may be driven alternately or simultaneously and in either direction at will.

In testimony whereof I have hereunto signed my name.

WILL ESPY CURTIS
